UNITED STATES PATENT OFFICE

SAMUEL H. NORTON, OF MEADVILLE, PENNSYLVANIA, ASSIGNOR TO HOOKLESS
FASTENER COMPANY, A CORPORATION OF PENNSYLVANIA

FASTENER

Application filed February 5, 1930. Serial No. 426,022.

My invention relates to articles employing slide fasteners and particularly to the manner in which the fastener is attached to the article.

5 The general object of my invention is to provide improved fastening means for fastening edges of separable parts of an article and in which there is no liability of the fastening means opening up under strain.
10 Slide fasteners have been successfully used on a large variety of articles including many items of clothing such as rubber overshoes, leggings, and coats. As is generally known in the art, a slide fastener consists of a pair of 15 stringers carrying fastener elements along their adjacent edges and a slider for progressively locking or releasing such elements. Heretofore it has been the practice to attach the flexible stringers by any suitable means 20 as by cementing or sewing to the adjacent edges of the separable portions of the article to be fastened and the fasteners have usually been securely connected to the article all along their entire length and especially at the end 25 of the fastener which is first to be opened by the slider. It will thus be seen that the force applied to the fastener is distributed along its entire length and is particularly effective near the ends of the fastener. When 30 the fastener is fully closed the slider is, of course, arranged at one end and is held from moving off the fastener by suitable stop elements. When lateral force is thus applied to the fastener in the locality of the slider, 35 there has been in many instances, a tendency for the slider to work back and allow the fastener to open up. In order to prevent such opening up of the fastener, various types of locking means have been devised for preventing 40 unintended movement of the slider. My invention aims to prevent such movement by attaching the fastener to the article in a novel manner and without any locking device 45 for the slider.

From another of its aspects, my invention consists of improved means for preventing inadvertent opening of a slide fastener particularly when the fastener is applied in a 50 so-called inverted position or with the slider

disposed at the lower end of the fastener when it is fully closed.

A more specific object of my invention is to extend the fastener stringers beyond the terminal point of attachment of at least one 55 of the stringers a sufficient distance to allow disposal of the slider beyond the line of transverse force applied to the fastener.

Other objects and advantages of my invention will appear more fully during the course 60 of the following specification.

In the accompanying drawings I have shown for purposes of illustration two embodiments which my invention may assume in practice. In these drawings: 65

Fig. 1 illustrates a portion of a garment embodying my invention.

Fig. 2 is an enlarged view of the end of the garment shown in Fig. 1 illustrating the invention on a larger scale.

Fig. 3 is a view similar to Fig. 2 showing the fastener partly opened.

Fig. 4 is a view similar to Fig. 2 illustrating another embodiment of my invention.

Fig. 5 is a horizontal sectional view of the 75 slider.

In order to explain the use of my invention, I have illustrated it in conjunction with a pair of knickers 6 having a knee fitting portion 7. As is usual in knickers, each of the 80 knee fitting portions has a slit 8 extending from the lower end of the garment to a substantial distance above the knee so as to allow the tightly fitting portions 9 and 10 to be separated when putting on and taking off 85 the garment. In order to fasten together the edges of the slit 8 and to connect the separable portions 9 and 10 a slide fastener generally designated 11 is sewed to the edges of the slit. As more plainly shown in Fig. 2, 90 the slide fastener comprises a pair of flexible stringers 12 and 13 having fastener elements 14 secured to their adjacent longitudinal edges. A slider 15 is movable along the stringers to engage and disengage the fastener elements in a manner well understood in the art, and in order to prevent removal of the slider from the stringers, suitable stop elements 16 are attached to the ends of the stringer adjacent the fastener elements. It 100

will now be noted that instead of the stringers terminating at the edge of the garment they are extended a sufficient distance to allow disposal of the slider beyond the edges of the garment when the fastener is fully closed. It will thus be seen that when tension is applied to the separable portions 9 and 10 the force transmitted to the fastener will be well above the slider and there will be no tendency for the slider to cam back along the fastener elements and allow the stringers to be separated.

In Fig. 4 there is illustrated an embodiment which may be preferred in many cases where it is desired not to extend the fastener beyond the edges of the garment. In this case one of the stringers 13 is sewed or otherwise attached to the article all along its entire length as by the line of sewing 17. The attachment of the other stringer 12 to its portion of the article as by the line of sewing 18 terminates a sufficient distance short of the end of the stringer so as to permit the slider to be disposed at a point where no lateral strain can be applied to the fastener. With one of the stringers thus secured to the article completely to its end, the end of the fastener is held in position allowing the slider to be easily moved upwardly when it is desired to open the fastener. Furthermore, in this form the fastener does not protrude beyond the article to which it is attached, the advantages of which will be apparent.

As will be seen in Fig. 5 the slider has a pair of diverging channels 19 which meet near the central part of the slider and merge into a single channel 20. It will be apparent that it is sufficient for the purposes of this invention to have the slider disposed beyond the terminal point of attachment of one of the stringers sufficiently to prevent any lateral force being applied to the fastener immediately opposite the diverging channels.

As a result of my invention it will be observed that in effect a suitable locking means has been devised for slide fasteners which requires no special mechanism on the slider and which will function equally well in any position of the fastener. This makes it especially desirable in so-called inverted applications of the fastener because some of the locking devices which will function very well when the slider is in normal position as in rubber overshoes will not give satisfaction when the fastener is inverted as in the application to a pair of knickers or leggings. It will, of course, be understood that my invention is equally useful in all types of applications of the fastener.

While I have in this application specifically described two embodiments which my invention may assume in practice, it will be understood that these embodiments are merely for the purposes of illustration and

description and that various other forms may be devised within the scope of my invention as defined in the appended claims.

What I claim as my invention is:

1. In an article having separable portions to be fastened, a slide fastener for fastening the same comprising fastener stringers secured to opposite edges of said separable portions, interlocking fastener elements on said stringers, a slider movable along said stringers for engaging and disengaging said elements, said slider being in continuous engagement with the elements of both of said stringers, stop means on said stringers for limiting the closing movement of said slider and preventing disengagement of the slider from the elements of either stringer, said stop means being located substantially beyond the terminal point of attachment of at least one of said stringers to prevent sidewise stress on said slider while the fastener is closed.

2. An article having a slit therein opening through the edge of the article, fastener stringers secured along the edges of said slit, one of said stringers attached along the entire length of said slit while the attachment of the other terminates at a point spaced from the open end of said slit, interlocking fastener elements on said stringers, a slider movable along the stringers for engaging and disengaging said elements, said slider being in continuous engagement with the elements of both of said stringers, stop means on the ends of said stringers adjacent the open end of said slit for limiting closing movement of the slider and preventing disengagement of the slider from the elements of either stringer, said slider when in limiting position being engaged with said unattached portion of one stringer whereby no sidewise stress is applied to the slider while closed.

In testimony whereof I affix my signature.
SAMUEL H. NORTON.
